ELECTROMAGNETICALLY ACTUATED GROUND ISOLATED RELAY

Roger L. Deal and Robert W. Hansen, San Jose, Calif.,
assignors to Jennings Radio Manufacturing Corpora-
tion, San Jose, Calif., a corporation of Delaware

Filed Jan. 3, 1966, Ser. No. 424

Term of patent 14 years

(Cl. D26—13)

FIG. 1 is a perspective view of the electromagnetically actuated ground isolated relay showing our new design;

FIG. 2 is a bottom plan view thereof; and

FIG. 3 is a top plan view thereof.

We claim:

The ornamental design for an electromagnetically actuated ground isolated relay, as shown.
